(57) **CLAIM**

The ornamental design for a dispense font, as shown and described.

DESCRIPTION

FIG. 1 is a front perspective view of a dispense font showing my new design;

FIG. 2 is a front elevational view thereof;

FIG. 3 is a side elevational view thereof;

FIG. 4 is a top plan view thereof;

FIG. 5 is a rear elevational view thereof; and,

FIG. 6 is a left side elevational view thereof.

The broken lines in the drawings are included for the purpose of illustration and form no part of the claimed design.
